UNITED STATES PATENT OFFICE

104,107

DESIGN FOR A WHEEL

J Harold Hunt and Harry J. Horn, Lansing, Mich.,
assignors to Motor Wheel Corporation, Lansing,
Mich., a corporation of Michigan

Application March 2, 1936, Serial No. 61,447

Term of patent 7 years

To all whom it may concern:

Be it known that we, J Harold Hunt and Harry J. Horn, citizens of the United States, residing in Lansing, in the county of Ingham and State of Michigan, have invented a new, original, and ornamental Design for a Wheel, of which the following is a specification, reference being had to the accompanying drawing, forming a part thereof.

In the drawing:

Figure 1 is a front elevational view of a wheel showing our new design;

Figure 2 is an enlarged sectional view taken on the line 2—2 of Figure 1; and

Figure 3 is an enlarged sectional view taken on substantially the line 3—3 of Figure 1.

The dotted line portion of Figures 2 and 3 represents a conventional form of bolting on flange which is concealed by the hub cap when the wheel is in use.

We claim:

The ornamental design for a wheel, as shown and described.

J HAROLD HUNT.
HARRY J. HORN.
